UNITED STATES PATENT OFFICE

172,334

BUCKLE OR SIMILAR ARTICLE

Milton Brock, Bayside, N. Y.

Application February 8, 1954, Serial No. 28,899

Term of patent 7 years

(Cl. D17—1)

To all whom it may concern:

Be it known that I, Milton Brock, a citizen of the United States, and a resident of Bayside, county of Queens, State of New York, have invented a new, original, and ornamental Design for a Buckle or Similar Article, of which the following is a specification, reference being had to the accompanying drawings, forming part hereof and in which:

Fig. 1 is a front elevational view of a buckle or similar article, showing my new design.

Fig. 2 is a top plan view.

I claim:

The ornamental design for a buckle or similar article, as shown.
